UNITED STATES PATENT OFFICE.

PERCY MERTON AND CHARLES S. MERTON, OF PARK RIDGE, NEW JERSEY.

SWEAT-BAND FOR HEAD-GEAR.

1,134,888.

Specification of Letters Patent.

Patented Apr. 6, 1915.

Application filed October 15, 1913. Serial No. 795,263.

To all whom it may concern:

Be it known that we, PERCY MERTON and CHARLES S. MERTON, citizens of the United States, and residents of Park Ridge, in the county of Bergen and State of New Jersey, have invented a new and Improved Sweat-Band for Head-Gear, of which the following is a full, clear, and exact description.

This invention has particular relation to improvements in headgear, including hats, caps and the like, and the invention comprehends an improved sweat band therefor.

More specifically, the invention is embodied in an improved sweat band which consists of a lower strip of leather, chamois or some similar material which can or cannot be washed, in conjunction with an upper strip or section of cloth primarily designed to match the interior of the hat or cap and to be sufficiently soft and flexible so as to permit the headgear to be blocked with the sweat band therein, thus avoiding the usual crease or ridge in the crown where hats or caps are blocked with the wide leather sweat band, especially due to its stiffness.

With the above and other objects in view, the invention resides more particularly in the peculiar combination and arrangement of parts which will be illustrated as a preferred embodiment in the accompanying drawings and described in the specification.

Reference is to be had to the accompanying drawings forming a part of this specification, in which similar characters of reference indicate corresponding parts in all the views, and in which—

Figure 1 is a perspective view of a conventional form of hat, the same being partly broken away and shown in section to illustrate the improved sweat band; Fig. 2 is an enlarged vertical sectional view of a fragmentary portion of the hat shown in Fig. 1; and Fig. 3 is a detail sectional elevation of the sweat band.

It is a well known fact that headgear provided with sweat bands as now generally employed and which consist of a wide comparatively stiff section of leather, cannot be secured within the hat or cap before the same is blocked without forming a crease or ridge in the crown, thus not only increasing the cost of manufacture but also resulting in an unsightly appearance if the headgear is blocked with the band secured in position. It is also known that the sweat band only contacts with the head for a short

or narrow space at its lower edge where secured to the crown of the hat or cap so that the upper part, comprising a greater portion of the band, is perfectly useless for the purpose for which it is designed and results in a corresponding increase of bulk and cost of manufacture and a corresponding unsightly appearance. It is my intention to obviate these objections, all of which will appear as the specification proceeds.

It must be understood that the device may be applied to various types of headgear, but in the illustrated embodiment a soft hat is shown which is provided with a crown and a partially stiffened rim 6 secured thereto as shown at 7, and having a surrounding band 8 attached thereto at the point of juncture of the crown and rim. The improved sweat band is indicated by the numeral 9 and embodies a lower narrow strip 10 of leather, chamois or other similar material which can or cannot be washed, and an upper and relatively wide section or strip 11 of cloth or other material which can or cannot be washed but which is essentially soft and flexible and designed to match the interior of the hat. This upper section may consist of a single piece of cloth or the like with its edges folded as shown at 12, but may further consist of a backing of some stiffening material 13 with the folds 12 turned over the edges thereof. The folds 12 are stitched as shown at 14, the stitching at the bottom being also engaged through the narrow leather strip 10 to secure the parts of the compound sweat band together, while the strip 10 is stitched through the rim and crown, as shown at 15. The function of such structure is apparent in the manufacture of hats and caps owing to the fact that the same can be blocked with the sweat band therein, whereas at present the wide section of stiff leather will form a crease or ridge in the crown in such a manner as to necessitate the securing of the sweat band in position after the hat or cap has been blocked. In the latter case the sweat band is not blocked to properly fit the hat or cap unless re-blocked or shaped, with a corresponding increase of cost in the manufacture and the same objectionable result. In providing such sweat bands for opera hats, especially collapsible ones, the cloth will permit the hats to be collapsed, whereas the continuous leather band will not permit this, and an advantage is derived

over the use of a sweat band constructed wholly of cloth, since the leather part is the only part which directly contacts with the head of the wearer, so that the full benefit 5 of such material as leather is derived in being cool and possessing better wearing qualities. The leather will also not adhere to the head and hair as will a cloth sweat band, especially if made of silk, satin or the 10 like.

Having thus described our invention, what we claim as new and desire to secure by Letters Patent is:—

1. A sweat band, comprising a lower narrow strip of relatively stiff material and a 15 comparatively wide upper strip of flexible material secured to the upper edge of the lower strip.

2. A sweat band, comprising a lower anchoring strip of leather and an upper cloth strip secured to the upper edge of the leather strip.

3. A sweat band, comprising a lower anchoring strip of leather, an upper cloth

strip of greater width than the leather strips 25 and secured to the upper edge of the leather strip and a backing of stiffening material secured to the said cloth strip.

4. The combination with an article of headgear, of a sweat band therefor including a lower strip of relatively smooth and stiff material adapted to contact with the head of the wearer, and an upper strip of flexible material adapted to match the headgear and having folded edge portions, said 30 upper strip being secured to the outer face of the lower strip and adapted to permit the headgear to be blocked with the band therein.

In testimony whereof we have signed our 40 names to this specification in the presence of two subscribing witnesses.

PERCY MERTON.
CHARLES S. MERTON.
